UNITED STATES PATENT OFFICE.

FREDERIC I. JOHNSON, OF FITCHBURG, MASSACHUSETTS, ASSIGNOR TO
MARY ELIZABETH JOHNSON, OF FITCHBURG, MASSACHUSETTS.

DESIGN FOR A BICYCLE-FRAME.

SPECIFICATION forming part of Design No. 35,391, dated December 3, 1901.

Application filed October 28, 1901. Serial No. 80,349. Term of patent 7 years.

To all whom it may concern:

Be it known that I, FREDERIC I. JOHNSON, a citizen of the United States, residing at Fitchburg, in the county of Worcester and Commonwealth of Massachusetts, have invented and produced a new and original Design for Bicycle-Frames, of which the following is a specification, reference being had to the accompanying drawing, forming a part thereof, and representing a side elevation of a bicycle-frame embodying my new and original design.

As shown in the drawing, the leading or material feature of my design consists of a brace rod, tube, or bar A, joined at its forward end to the steering-head B and at its rear end to the seat-post C and being connected at its central section to the backbone

D by a short bar E, said backbone D, steering-head B, strut F, rear fork G, and brace H being arranged in the usual form of bicycle-frames now in common use and known as "diamond" frames. The several bars constituting the framework are straight, with the exception of the truss A, which is slightly curved, with the convex side uppermost.

Having described my invention, what I claim as new, and desire to secure by Letters Patent, is—

The design for the bicycle-frame as herein shown and described.

Dated this 21st day of October, 1901.

FREDERIC I. JOHNSON.
